Claims priority, application Switzerland May 17, 1954

2 Claims. (Cl. 200—146)

Lever switches for heavy currents are known, which are provided with two current carrying switching points, said switching points being guided in such manner that they will open and close one after the other with the operating mechanism reversing its direction for each make and break. There also exist lever switches with one main and one auxiliary switching point where the auxiliary contact takes over the duty of making and breaking the circuit; it is always the first to close and the last to open the circuit. Another method, which employs lever switches with one main and one secondary switching point, specifies that the main contact opens ahead of the secondary contact when breaking the circuit and that this sequence is reversed for the making of the circuit. Finally there is a method known which employs two current carrying power switches working in parallel which are guided in such manner that the switching point which opens last will break, and the switching point which opens first will make the circuit.

An object of the invention is to provide a lever switch with two parallel and current carrying switching points, one of which will always be the last to be opened as well as the last to be closed. It is the basic characteristic of the invention that the moveable contact of that switching point, which will always be the last to be active, is located on a bellcrank lever, said lever being subjected to a compressive force and mounted to pivot at the end of a single-armed lever, said single-armed lever carrying the moveable contact of the second switching point, and that the free arm of said bellcrank lever is connected by means of a steering arm to another single-armed lever which in turn is linked to the first single-armed lever carrying the moveable contact of the second switching point and forming a knee joint with a driving crank, which turns always in the same direction, said knee joint being in its stretched position when the switch is closed.

A practical example of the invention is presented in somewhat diagrammatic form in Figs. 1-4 of the drawing which picture sequentially different positions of the switch contact actuating mechanism. Fig. 1 shows the switch in the "on" position, i. e. with the switch contacts closed; Fig. 3 shows the switch in the "off" position, i. e. with the switch contacts open; and Figs. 2 and 4 show, respectively, the positions of the switch actuating mechanism immediately before breaking, and immediately before making of the circuit controlled by the switch contacts.

With reference now to the drawings, numeral 1 indicates the base plate of the switch and upon which the contact actuating mechanism is mounted. The base plate carries stationary contact elements 2, 3 which with their moveable counter contact elements 2a, 3a mounted on the moveable switch mechanism form the current carrying switching points which are, electrically speaking, in parallel. The switching point 2, 2a has the duty to make the circuit and the stationary contact 2 is provided with laminated, or finger, contacts which engage practically simultaneously the moveable counter part 2a thereby di-

2

viding the load and keeping the mechanical and thermal stresses to a minimum. The switching point 3, 3a serves as the circuit breaker; its contacts are massive block contacts which can endure a certain amount of wear caused by the cut-off arc. During one make-and-break cycle the switching point 3, 3a will always be the last to open and the last to close. The moveable contact 2a of the switching point 2, 2a is located at the outer end of a single-arm lever 4 mounted pivotally at 12 at its opposite end on a bracket 5 extending laterally outward from the base plate 1. The moveable contact 3a of the switching point 3, 3a is located on and at the outer end of one arm 6a of a bellcrank lever 6 mounted pivotally at 13 intermediate its arms to the outer end of lever 4. Force is applied to lever 6 by a helical compression spring 7 which is connected at 14 to, and acts on, the other arm 6b of lever 6, the opposite end of the spring 7 being secured at 15 to bracket 5.

Arm 6b of bellcrank lever 6 is also connected at its outer end by a sliding pivot connection 16 to one end of a steering arm 8, the opposite end of arm 8 being pivotally connected at 17 to an intermediate portion of a single-arm dog-leg-shaped lever 9. One end of lever 9 is connected pivotally at 18 to lever 4 intermediate the ends of the latter, and the opposite end of lever 9 is pivotally connected at 19 to the outer end of a crank 11, the inner end of this crank being fixed to a shaft rotatable about its axis 19.

The dog-lever 9 forms a knee joint with the driving crank 11 which is arranged to always rotate in the direction indicated by the arrow and will assume a dead-center position when the switch contacts are closed, the position indicated in Fig. 1, wherein it will be seen that the crank axis 19, crank pivot 18 and pivot 10 all lie in a straight line.

The driving crank 11 can be operated either manually, or by a motor or a spring driven device. It performs one complete revolution during one circuit breaking and making operation.

When, for the purpose of breaking the circuit, crank 11 is set in motion in the direction indicated by the arrow, lever 9 will deflect the knee joint, and lever 4 will then begin to turn about its pivotal mounting point 12 at the bracket 5. The switching point 2, 2a then opens. Due to the pivotal mount of the lever 4 the position of bellcrank lever 6, which is then using the switching point 3, 3a as its fulcrum, will also change. The spring 7 will now expand longitudinally and its pressure will lessen. However, the contacts of the switching point 3, 3a will still be subject to, at least, the same pressure because, due to the displacement of the bellcrank lever 6, the effective leverage of the spring 7 has increased (see Figure 2). When the crank 11 continues its turning motion the steering arm 8 will take up the pressure of the spring after 55 the contacts 2 and 2a have reached a certain distance from each other and will open the switching point 3, 3a. The components of the switch will then take up the positions shown in Figure 3 and the spring 7 will be set again.

At the closing of the switch, which now follows, the contacts of the switching point 2, 2a will engage first. The steering arm 8, lever 9 and the still turning crank 11 will retard the closing of the movable contact 3a of the switching point 3, 3a (see Figure 4) but these will ultimately close as the knee of the dog-leg lever 9 rises due to further rotation of crank 11 causing steering arm 8 to rise which results in rotation of bellcrank lever 6 and hence movement of contact 3a into engagement with contact 3.

In conclusion it will be understood that while I have described and illustrated one practical embodiment for the invention various changes in the construction and ar-

angement of parts may be made without departing from the spirit and scope of the inventive concept as defined in the appended claims.

I claim:

1. A lever actuated switching mechanism comprising two current carrying and parallel arranged sets of switching points, one of said sets of switching points being the last to be opened as well as the last to be closed, the movable contact element of said set of switching points that is last to be opened and closed being located on one arm of a bellcrank lever, said bellcrank lever being subjectable to a force tending to rotate the same about its pivot and said bellcrank lever being pivotally mounted at the end of a first single-arm lever, and said first single arm-lever carrying the movable contact element of said other set of switching points, the other arm of said bellcrank lever having pivotally connected thereto one end of a steering arm, the other end of said steering arm being pivotally connected to an intermediate portion of a second single-

arm lever, one end of said second single-arm lever being pivotally connected at an intermediate point on said first single-arm lever and the other end of said second single-arm lever being pivotally connected to the outer end of a crank arm rotatable always in the same direction, said second single-arm lever forming a knee joint with said crank and which joint occupies a dead-center position when said sets of switching points are closed.

5 10 15 2. A lever actuated switching mechanism as defined in claim 1 wherein the contact pressure at the set of switching points which is last to be opened and closed is effected by a spring connected between said other arm of said bellcrank lever and a stationary point on the base plate upon which the switch actuating mechanism is mounted.
